UNITED STATES PATENT OFFICE.

MAX KOLLER, OF WINTERTHUR, SWITZERLAND.

WATCH-STAND.

No. 835,762.

Specification of Letters Patent.

Patented Nov. 13, 1906.

Application filed September 27, 1905. Serial No. 286,333.

To all whom it may concern:

Be it known that I, MAX KOLLER, a citizen of the Swiss Confederation, and a resident of Winterthur, Switzerland, have invented certain new and useful Improvements in Watch-Stands, of which the following is a specification.

The invention relates to an improved holder or support for timepieces, the object 10 being to provide means whereby the face or dial of the timepiece may be temporarily illuminated when it is desired to inspect the same, a further object being to effect such temporary illumination without the aid of a hand-operated switch or other similar expedient 15 difficult to locate in a darkened room.

The invention consists in the provision of such a support serving to hold or receive the timepiece or the like and provided with 20 lighting means—such, for instance, as an incandescent lamp and a source of current therefor—together with suitable controlling devices associated with said lamp and source of supply 25 serving to normally cut off the latter and serving to cut in the supply upon the application of pressure to said lighting means, the lamp being automatically cut out when said pressure is released.

The invention will be more fully described 30 in connection with the accompanying drawings and will be more particularly pointed out and ascertained in and by the appended claims.

Figure 1 is a vertical section, partly in elevation, of an improved form of holder embodying the main features of my invention and adapted to be suspended from a hook or the like. Figs. 2 and 3 are front and side elevations, respectively, of a modified form of 40 holder adapted to be supported on a stand or shelf.

The holder, as shown, consists of a main body portion *a*, provided with a hook or suitable support *b* for the watch, a container *c* for the chain of the watch or for other purposes, and a receiver *d*, provided with a lower wall *e*, extending forwardly a short distance from the rear or main body portion *a*.

In Figs. 2 and 3 the main body portion is 50 provided with a container *c'* and a rear leg or standard *a'*, adapted to support the holder upon a shelf, stand, or the like. A casing *g* is provided and is adapted to be supported in the receiver *d* and upon the lower wall *e*

thereof, said casing containing suitable lighting means—such, for instance, as an incandescent lamp *h*—which, as shown, is located in a manner to throw rays of light downwardly through the open bottom wall of the receiver *d*. Any suitable source of current-supply—such, for instance, as a dry battery—may be provided within the casing *g*. The casing is also provided with means for cutting in and cutting out the supply of current to said lamp, which means consists, as 65 shown, of a push-button *i*, projecting through the lower wall of the casing *g* above the wall *e*. A spring *k*, secured to the wall *e*, normally supports the casing *g* and maintains the push-button *i* out of contact with the wall *e*. 70 When it is desired to illuminate the face of the watch, pressure is applied in the direction of the arrow *A* against the action of the spring *k*, forcing the casing *g* and button *i* downwardly, the latter engaging the wall *e* 75 and being forced into the casing, thereby closing the lamp-circuit, the rays of light passing through the lower open portion of the receiver *d*, as will be obvious by reference to Fig. 1. Where the casing *g* is located in the 80 manner just described, I provide a reflector *f* to cast the rays of light upon the face of the watch. From the foregoing it will be obvious that where the watch-holder is situated in a dark place the user after locating the 85 holder can more easily find the casing *g* and press downwardly thereon and light the lamp than would be the case if the lamp were controlled by a switch or push-button. The device of the invention may be useful 90 when located upon a dresser to momentarily light up portions thereof when it is not desired to employ the ordinary illuminating means.

I claim—

1. A watch holder or stand comprising in combination a support *b* for the watch, an electric lamp *h*, a casing therefor provided with circuit-closing means *i* and a source of current, a receiver *d* for said casing provided with a reflector *f* adapted to throw the rays of light upon the watch, and a spring *k* engaging the casing and normally holding the latter in a position to open said circuit-closing means. 95

2. A watch-holder comprising in combination a support for the watch, a casing provided with lighting means, a source of supply 100

105

therefor, and circuit-closing mechanism, said mechanism normally cutting off supply and engaging the watch-holder and serving to cut in the supply when pressure is applied to the casing.

3. A watch-holder comprising in combination a support for the watch, a casing provided with lighting means, a source of supply therefor, and circuit-closing mechanism adapted to engage the watch-holder to close circuit with the lamp and its supply, and means normally preventing closure of the circuit.

4. A watch-holder comprising in combination a support for the watch, an electric lamp, a casing therefor provided with circuit-closing means and a source of current, a reflector casting rays of light upon said watch, and a spring normally holding the casing in position to open said circuit-closing means. 15 20

In testimony whereof I have hereunto set my hand in presence of two witnesses.

MAX KOLLER.
